US0D1016622S

(12) **United States Design Patent** (10) **Patent No.:** **US D1,016,622 S**
(45) **Date of Patent:** **** Mar. 5, 2024**

(54) **AEROSOL DISPENSER**

(71) Applicant: **SENSORY CLOUD, INC.**, Boston, MA (US)

(72) Inventors: **Robert Brunner**, Glen Ellen, CA (US); **Zu-Ning Chen**, San Francisco, CA (US); **Emerson Holladay**, San Francisco, CA (US)

(73) Assignee: **SENSORY CLOUD, INC.**, Boston, MA (US)

(**) Term: **15 Years**

(21) Appl. No.: **29/795,266**

(22) Filed: **Jun. 17, 2021**

(51) LOC (14) Cl. **09-01**

(52) U.S. Cl.

USPC **D9/688**; D9/504; D9/549

(57) **CLAIM**

The ornamental design for an aerosol dispenser, as shown and described.

DESCRIPTION

FIG. 1 is a top, front, right side perspective view of an aerosol dispenser showing our new design.

FIG. 2 is a bottom, back, left side perspective view thereof.

FIG. 3 is a front elevational view thereof.

FIG. 4 is a right side elevational view thereof.

FIG. 5 is a left side elevational view thereof.

FIG. 6 is a rear elevational view thereof.

FIG. 7 is a top plan view thereof; and,

FIG. 8 is a bottom plan view thereof.

The broken lines in the figures represent features of the aerosol dispenser that form no part of the claimed design.

1 Claim, 7 Drawing Sheets
